SAFETY CASEMENT SASH UPPER LOCK

William B. Lang, West Palm Beach, Fla.

Application February 14, 1940, Serial No. 318,948

8 Claims. (Cl. 292—69)

This invention relates to closure fasteners and more particularly to a lock or fastener for use in connection with the sashes of casement windows.

5 An object of this invention is to provide a closure fastener of this character which is adapted to lock the upper portion of a sash so as to prevent unauthorized opening of the window from the outside and to hold the sash tightly against 10 the window frame irrespective of whether the sash is warped or straight.

A further object of this invention is to provide a closure fastener of this character which is adapted to be used as a supplement to the present 15 holding means for holding the casement window in either open or closed position.

A still further object of this invention is to provide a closure fastener which is simple in construction and arrangement, strong, durable, compact, simple to install relative to the window, thoroughly efficient in its use, and conveniently operated to lock or release the sash in addition to being inexpensive to manufacture.

25 A further object of this invention is to provide a closure fastener for a casement sash which is adapted to be interposed between the sash and an inside screen which is provided with operating means extending through the screen frame so that the lock or fastener may be operated without removal of the screen frame.

30 A further object of this invention is to provide a structure of this kind wherein the operating means for the fastener is mounted on the screen frame so that the screen frame may be readily removed from the window frame, the operating means being of a removable or detachable character.

35 Embodying the aims aforesaid and others which 40 may hereinafter appear, my invention consists of the novel construction, combination and arrangement of parts, as will be more specifically described and illustrated in the accompanying drawings, wherein are shown embodiments of my 45 invention, but it is to be understood that changes, variations and modifications may be resorted to which fall within the scope of the invention as claimed.

50 In the drawings:

Figure 1 is a fragmentary front elevation partly in section of a closure fastener constructed according to an embodiment of this invention.

55 Figure 2 is an enlarged fragmentary sectional view taken on the line 2—2 of Figure 1.

Figure 3 is a sectional view taken on the line 3—3 of Figure 2,

Figure 4 is a sectional view taken on the line 4—4 of Figure 3,

Figure 5 is a sectional view taken on the line 5—5 of Figure 1,

Figure 6 is a fragmentary rear elevation of the screen frame structure having a modified form of operator for the closure fastener disclosed in Figures 1 to 5, inclusive,

10 Figure 7 is a detail side elevation partly in section of the operator shown in Figure 6,

Figure 8 is a fragmentary plan view of the operating shaft for this device before it is cut off to the desired length to fit the particular window 15 and screen structure,

Figure 9 is a fragmentary view from the outside of a double casement window having a single locking device secured thereto, and

Figure 10 is a sectional view taken on the line 20 10—10 of Figure 9.

Referring to the drawings, numeral 10 designates generally a window frame structure which is provided with a stop 11 against which a casement sash 12 is adapted to engage. The sash 12 is hinged at one edge to the frame structure 10 and is releasably held against the stop 11 by conventional holding and locking means (not shown). The hinges for the sash 12 are on the edge thereof opposite from the edge shown in 30 Figures 1 and 2.

A screen frame structure 14 is adapted to engage the inner edge of the stop 11 and is provided with a screen panel 13. The screen frame 14 is provided with a rabbeted lower edge portion 35 15 which is engageable with a rabbeted rail 16 secured between the vertical sides of the window frame structure 10.

In order to provide a means whereby the window sash 12 may be releasably locked in the 40 frame structure 10 and against the stop 11 in such a manner so as to tightly hold the inner face of the sash 12 against the stop 11, I have provided a locking structure which is secured to the stop 11 between the sash 12 and the screen frame 14. 45 The locking structure for locking the sash against the stop 11 comprises a substantially rectangular housing 17 which is provided with an open upper side and is also provided with an end flange 18 through which fastening devices 19 engage so as to 50 tightly secure the housing 17 against the stop 11. The housing 17 comprises a lower wall 20, end walls 21 and 22 and side walls 23 and 24. The side wall 23 is the outer side wall and is pro- 55

vided with an opening 25 through which a looped keeper 26 is adapted to engage. The keeper 26 extends inwardly at right angles to the inner face of the sash 12 and is formed integral with a base 5 plate 27 secured by fastening devices 28 to the inner side of the upper rail of the sash 12.

A frame structure generally designated as 29 is mounted within the housing 17 and comprises a base member 30 having a right angle extension 10 31 and a guide bar 32 extending in parallel relation to the lower wall 20 of the housing 17. The base member 30 is fixedly secured to the lower wall 20 by fastening devices 33 in the form of rivets or the like. The guide member 32 extends 15 in the direction of the wall 21 and is provided with a right angle extension 34 confronting the inner face of the wall 21. The extension 34 is secured to the wall 21 by fastening devices 35 in the form of rivets or the like.

20 The fastener includes a horizontally disposed latching or locking structure slidably mounted on the frame structure 29 for correlation with the keeper 26 to releasably fasten, latch or lock the sashes together. The said latching or locking structure is substantially of U-form open at its forward end and closed at its rear end and it is bodily movable endwise and bodily movable laterally simultaneously with its endwise movement. The latching or locking structure includes a locking shank or lower arm 36 which is slidable on 25 the guide member 32 and is constructed in the form of an elongated flat bar which is provided with an inclined forward end 37 which is inclined outwardly from the inner edge of the shank 36 as shown in Figure 4. The shank 36 is slidably mounted on the guide bar 32 by means of a bolt or headed pin 38 which engages through a cam track generally designated as 39. The headed pin 38 is provided in the form of a short 30 bolt and a nut 40 is threaded onto the bolt 38. The cam track 39 has a straight rear portion 41 and an obtusely inclined forward portion 42. By providing a cam track as shown in Figure 4, when the shank 36 is moved endwise on the guide 35 member 32, the shank 36 is also given a lateral or inward movement so as to provide a wedging action relative to the keeper 26.

The shank 36 merges at its rear end into the lower end of a right angle extension or bight 43 50 which merges at its upper end into an elongated upper arm 44 disposed in parallel relation to the shank 36. The arm 44 overlies the shank 36 and is provided with a reduced extension 45 having a cam engaging nose 46. The cam engaging part 55 46 is adapted to engage a cam member 47 which is secured at the opposite ends thereof to the walls 23 and 22, respectively. The cam member or track 47, inclined inwardly from the opening 25 and the reduced part 45 of the shank 36 shifting member 44 is substantially longer than the shank 36 so that the shank 36 will be shifted laterally to a position substantially parallel with the forward wall 23 when the shank 36 is in an extended or locking position as shown in dotted 60 lines in Figure 4.

The shank 36 is yieldably urged to a retracted position by means of a contracting spring 48 which at one end thereof is secured to a forwardly extending member 49 formed with the extension 34. The forward end of the spring 48 is provided with a loop or eye 50 which engages a headed pin 51 carried by the arm 44 forwardly of the rear end thereof. The rear end of the 75 spring 48 is provided with an eye or loop 52 en-

gaging through an aperture 53 provided in the extension 49.

In order to provide a means whereby the shank 36 may be extended to an operative or locking position, I have provided a shaft 54 which 5 is journaled through the side wall 24 of the housing 17. The shaft 54 has fixedly secured thereto a bolt operating lever 55 and the lever 55 is provided with a headed pin 56 adjacent the free end thereof. A shank extending spring 57 10 is provided at one end with a loop 58 engaging in an opening 59 provided in an extension 60 which is formed with the rear portion of the arm 44. The extension 60 extends laterally or inwardly of the arm 44. The spring 57 is provided with a 15 straight portion 61 which has a loop 62 engaging about the pin 56. The loop 62 is formed by twisting the wire 61 in the manner such that the loop 62 cannot readily become loosened. In the same manner the loop 58 is formed by twisting 20 the wire at the inner end of the spring 57 and threading the free end of the wire through one of the convolutions of the spring 57.

The operating shaft 54 has a collar 63 secured thereto by means of a pin 64 and the shaft 54 25 is preferably provided with a number of peripheral grooves 65 with a hole 66 adjacent each groove 65. In this manner the shaft 54 can be initially constructed substantially long so that when the housing 17 is secured to the stop 11, the 30 shaft 54 can be cut off for the desired length so that it will extend into an opening 67 provided in the screen frame 14. A sleeve 68 is removably mounted on the shaft 54, the sleeve 68 engaging loosely in the opening 67 provided in the screen 35 frame 14. The sleeve 68 is provided with a pair of diametrically opposed longitudinal slots 69 within which a pin 70 engaging through a selected opening 66 of the shaft 54 engages. In this manner the pin 70 will hold the sleeve 68 40 against rotation relative to the shaft 54 but will permit endwise movement of the sleeve 68 relative to the shaft 54 when it is desired to remove the screen frame 14 from the window frame structure 10.

The sleeve 68 is provided with a reduced portion 71 which is fixed by means of a pin 72 in one end of a handle or operator 73. An escutcheon plate 74 is provided with an opening 75 within which the reduced portion 71 of the shaft or sleeve 68 is loosely received so that the sleeve 68 may have rotation relative to the escutcheon 74 when this plate is secured by fastening devices 76 to the frame 14.

In Figures 6 and 7, there is disclosed a modified form of operator for the shaft 54. In this modified form a sleeve 68^a is provided similar to the sleeve 68 which has a slot 69^a to receive the pin 70. The sleeve 68^a is provided with a reduced portion 77 which extends through an axial opening provided in a pulley 78. The pulley 78 is fixed to the reduced part 77 by means of a key or pin 79. A plate or escutcheon 80 is provided with an opening 81 through which the reduced part 77 engages and the plate 80 is mounted between the outer end of the sleeve 68^a and the inner side of the pulley 78. The plate 80 is provided with an arcuate shield or hood 82 which engages about the pulley 78 so as to prevent a flexible operator 83 from riding off of the pulley 70 78. The operator 83 is constructed in the form of a cord which is fixed intermediate its ends, as at 84 to the pulley 78. The operator 83 is provided with a ring 85 at one end and with a ring 86 at the other end. These rings 85 and 86 are 75

adapted to depend downwardly of the inner side of the screen frame structure 14. The pulley 78 is provided with an opening 87 through which a tool is adapted to be extended so that fastening devices 88 in the form of screws may be extended through the plate 80 in order to fasten this plate on the inner side of the screen sash or frame.

In the use and operation of this device, the housing 17 is secured to the underside of the stop member 11 between the casement sash 12 and the screen frame or sash 14. The screen frame 14 is provided with an opening 67 through which the sleeve 68 loosely engages. The screen frame 14 in the present instance is removably held in the window frame structure 10 by means of a plurality of spring pressed headed members 89 engaging in sockets 90 which are countersunk in the frame 14. The frame 10 is provided with keepers 91 confronting the headed members 89. When it is desired to extend the shank 36, the operator handle 73 is swung one half turn to the left so as to rotate the shaft 54. This rotation of the shaft 54 will swing the spring tensioning lever 55 in a downward movement. The lever 55 will be swung downwardly to the left until the forward end of the spring 57 is disposed above the axial center of the shaft 54. In this position the spring 57 will be of a greater tension than the spring 48 so that the shank 36 will be moved forwardly with the slide pin 38 engaging in the cam track 39. Endwise movement of the shank 36 to an extended position will initially move the shank 36 along the straight cam track portion 41 and when the slide pin 38 engages the obtusely inclined slot or a cam track 42, the shank 36 will be forced inwardly of the forward wall 23 of the housing. At this time also the shank shifting arm 44 will engage at its forward end the cam member 47 so that the shank 36 will be prevented from pivoting on the slide member 38. Inward movement of the shank 36 as it is moving transversely through the keeper 26 will pull the keeper 26 inwardly and pull the casement sash 12 against the outer face of the stop 11. In this manner if the sash 12 is slightly warped, the locking of the keeper 26 by the shank 36 will hold the sash 12 tightly against the stop 11 notwithstanding the warped condition of the sash 12.

In the event it is desired to remove the screen 14 from the window frame this may be accomplished by tilting the frame 14 from its upper edge and then pulling the frame 14 upwardly and inwardly so as to release the rabbeted portion 15 from the rabbeted portion 16. The sleeve 68 is rotatably carried by the screen frame 14 and by providing the slot 69 in the sleeve 68, the screen 14 can be removed from the frame 10 without disturbing the housing member 17 as the pin 70 will slide out of the slot 69.

Furthermore, by providing the slotted sleeve 68 the casement sash may be opened in the conventional manner when the shank 36 is retracted. It will thus be seen that this locking structure does not interfere with the opening or closing of the sash 12 with the screen 14 within the frame 10.

In Figures 9 and 10 there is disclosed a casement window structure embodying a pair of hinged sashes 12^a and 12^b which are hinged to the frame 10^a on their outer vertical edges as at 89 and 90, respectively. A housing 17 is disposed between the screen member 14^a and the casement sash 12^a and is constructed and operated in the same manner as the housing shown in Figures 2 to 5. The sash 12^a is provided with a rabbeted

inner vertical edge 91 which overlaps the inner rabbeted vertical edge 92 so that when the operator 73 is actuated to lock the sash 12^a both sashes 12^a and 12^b will be tightly held in the frame 10^a. The screen frame 14^a is made in one piece and is provided with hooks 93 on its opposite vertical edges to facilitate the removal thereof.

While the operator 73 has been shown with the structure in Figures 9 and 10, it will be obvious that the pulley operator shown in Figures 6 and 7 may optionally be employed in place of the handle 73 in either Figures 9 and 10 or in the structure shown in Figures 1 to 5.

In Figure 8 there is shown a shaft 54 similar in every detail to the shaft shown in Figure 2, except that the shaft shown in this figure is considerably longer so that when the housing 17 is mounted in the window frame structure this shaft may be cut off at any groove or weakened part 65 in order that the shaft 54 will not extend entirely through the screen frame. The pin 70 may be inserted in the outermost hole 66 after the shaft 54 has been cut to the desired length.

As shown in Figure 2, the sleeve 68 may have an annular shoulder 71^a engaging through the opening 75 of the escutcheon 74 so that the sleeve 68 will be rotatable in the escutcheon 74 when this latter part is fixed to the screen frame 14. In like manner the sleeve 68^a may have an annular shoulder or bearing 77^a engaging in the opening 81 of the plate 80.

What I claim is:

1. A closure fastener comprising a housing, a frame in said housing, a locking shank slidable relative to the frame, a part fixed to the shank 35 and slidable therewith, said frame having a cam track therein, a part fixed to said shank engaging in said cam track, a cam member fixed to said housing forwardly of the frame and engageable with said first part on the forward endwise movement of the shank and coacting with said cam track to shift said shank and first part laterally coactive with on the forward endwise movement of said shank and first part, and operating means connected to said first part and shifting said 45 shank and first part in unison.

2. A closure fastener comprising a housing, a frame in said housing, a locking shank slidable relative to the frame, a part fixed to the shank 50 and slidable therewith, said frame having a cam track therein, a part fixed to said shank engaging in said cam track, a cam member fixed to said housing forwardly of the frame and engageable with said first part on the forward endwise movement of the shank and coacting with said 55 cam track to shift said shank laterally coactive with endwise movement of said shank and first part, yieldable means constantly urging said shank to a retracted position, a rockable shank extending lever, and tensionable means connecting said lever with said shank.

3. A closure fastener comprising a housing, a frame in said housing, a locking shank slidable relative to the frame, a part fixed to the shank 65 and slidable therewith, said frame having a cam track therein, a part fixed to said shank engaging in said cam track, a cam member fixed to said housing and engageable with said first part and coacting with said cam track to shift said shank 70 laterally coactive with endwise movement thereof, yieldable means constantly urging said shank to a retracted position, a rockable shank extending lever, tensionable means connecting said lever with said shank, an operating shaft fixed to said 75

- lever, a pin fixed to said shaft and projecting laterally thereof, a slotted sleeve removably telescoping said shaft, and an operator fixed to said sleeve.
5. 4. A closure fastener comprising a housing, a frame in said housing, a locking shank slidable relative to the frame, a part fixed to the shank and slidable therewith, said frame having a cam track therein, a part fixed to said shank engaging in said cam track, a cam member fixed to said housing and engageable with said first part and coacting with said cam track to shift said shank laterally coercive with endwise movement thereof, yieldable means constantly urging said shank to a retracted position, a rockable shank extending lever, tensionable means connecting said lever with said shank, an operating shaft fixed to said lever, a pin fixed to said shaft and projecting laterally thereof, a slotted sleeve removably telescoping said shaft, and a right angularly disposed handle fixed to said sleeve.
5. A closure fastener comprising a housing, a frame in said housing, a locking shank slidable relative to the frame, a part fixed to the shank and slidable therewith, said frame having a cam track therein, a part fixed to said shank engaging in said cam track, a cam member fixed to said housing and engageable with said first part and coacting with said cam track to shift said shank laterally coercive with endwise movement thereof, yieldable means constantly urging said shank to a retracted position, a rockable shank extending lever, tensionable means connecting said lever with said shank, an operating shaft fixed to said lever, a pin fixed to said shaft and projecting laterally thereof, a slotted sleeve removably telescoping said shaft, a pulley fixed to said sleeve, a flexible operator fixed intermediate its ends to and depending from opposite sides of said pulley, an arcuate shield engaging over a portion of said pulley, an upstanding plate encompassing said second shaft, interposed between the pulley and said sleeve and supporting said shield, and means for detachably securing said plate stationary.
6. A closure fastener for use with a looped keeper comprising a housing, a frame in said housing including a base and an offset shank guide member, said member having a cam track therein provided with a rear portion parallel with an edge of said member and a forward portion disposed on an obtuse angle relative to said rear portion, a locking shank slidable on said member, means carried by said shank engaging in said cam track, a shank shifting arm fixed to said shank and disposed in parallel relation thereto, the forward end of said arm projecting forwardly beyond the forward end of said shank, a cam member fixed to said housing and disposed in a position for engagement with said arm upon movement of said shank to an extended locking position, a bolt retracting spring connected at one end to said frame and at the other end to said arm, an operating shaft journalled in said hous-
- ing, a lever fixed to said shaft in said housing, a headed pin carried by said lever, a shank extending spring fixed at one end to said headed pin and at the other end to said arm adjacent the rear thereof, a laterally projecting pin carried by 5 said shaft, a slotted sleeve removably engaging said shaft, said latter pin engaging in the slot of said sleeve, an operator fixed to said sleeve, said shank extending spring being disposed at one side of the axial center of said shaft when 10 said shank is in retracted position, and said spring being disposed at the opposite side of the axial center of said shaft when said bolt is in extended position.
7. A closure fastener for correlation with a keeper to latch the latter, said fastener comprising a housing into which the keeper is adapted to extend, a frame within the housing formed with a cam track, cam means within the housing and spaced from said frame, an endwise bodily 20 shiftable latching structure slidably mounted on said frame and including a part coacting with said track for slidably connecting the latching structure to said frame and for shifting the latching structure laterally on the endwise movement of said structure, said structure including an upper arm engageable with said cam means for shifting the structure laterally on the forward endwise movement of the latter, said structure including a lower arm for disposing in latching 30 engagement with the keeper on the shifting of said structure endwise in a forward direction, resilient means connecting the upper arm of said structure to said frame, and shifting means for said structure resiliently connected to said upper 35 arm.
8. A closure fastener for correlation with a keeper to latch the latter, said fastener comprising a housing into which the keeper is adapted to extend, a frame within the housing formed with 40 a cam track, cam means within the housing and spaced from said frame, an endwise bodily shiftable latching structure slidably mounted on said frame and including a part coacting with said track for slidably connecting the latching structure to said frame and for shifting the latching structure laterally on the endwise movement of said structure, said structure including an upper arm engageable with said cam means for shifting the structure laterally on the forward endwise 50 movement of the latter, said structure including a lower arm for disposing in latching engagement with the keeper on the shifting of said structure endwise in a forward direction, resilient means connecting the upper arm of said structure to 55 said frame, a lever movable in an arcuate path, a resilient connection between said lever and the upper arm of said structure for bodily moving the latter endwise in one direction of the movement of the lever, and rotatable means for operating the lever to provide for the forward endwise shifting of said structure.
- 60

WILLIAM B. LANG.
